Tea Service.

Wm Parkin.

Design for Tea-Service.

4211

PATENTED JUL 5 1870

Inventor

William Parkin

Filed June 18, 1870

United States Patent Office.

WILLIAM PARKIN, OF TAUNTON, MASSACHUSETTS, ASSIGNOR TO HENRY G. REED,
GEORGE BRABROOK, AND HENRY H. FISH, OF SAME PLACE.

Design No. 4,211, dated July 5, 1870.

DESIGN FOR TEA-SERVICE.

The Schedule referred to in these Letters Patent and making part of the same.

To all whom it may concern:

Be it known that I, WILLIAM PARKIN, of Taunton, in the county of Bristol and State of Massachusetts, have invented a new and useful Design for a Tea-Service; and I do hereby declare the following to be is a full, clear, and exact description of the same, reference being had to the accompanying drawings making a part of this specification, in which the figure is a view in perspective.

The nature of my design is fully represented in the accompanying drawings of a tea-pot to which reference is made.

The body *a* of the pot is of the form an egg, cut transversely near the middle and near the smaller end.

The larger section is the bottom of the pot.

At the bottom of the pot is an outwardly-flaring flange, *b*, to which is hinged, and in which rests, the cover *c*.

The cover is ornamented with a central boss, *d*, from which projects upward a stem, *e*, which bears two or more flanges, *f*, with milled edges.

On the sides of the handle *h* and of the spout *i*, are floriated ornaments in bas-relief, and on the sides of the handle there are, in addition, series of transverse ridges with depressions between them, also in bas-relief.

Having thus described my invention,

What I claim as new, and desire to secure by Letters Patent, is—

The design for a tea-service, as herein shown and described.

WILLIAM PARKIN.
